Primary Examiner—Catherine R Oliver*(74) Attorney, Agent, or Firm*—Armstrong Teasdale, LLP**(57) CLAIM**

The ornamental design for a termite station container, as shown and described.

DESCRIPTION

FIG. 1 is a front perspective of a termite station container according to my new design;

FIG. 2 is a front elevational view thereof;

FIG. 3 is a top plan view thereof;

FIG. 4 is a right side elevational view thereof, the left side elevational view being a mirror image thereof;

FIG. 5 is a bottom plan view thereof; and,

FIG. 6 is a rear elevational view thereof.
